UNITED STATES PATENT OFFICE.

JOHN D. MORGAN, OF SUMMIT, NEW JERSEY.

TYPOGRAPHIC MACHINE.

1,056,042.

Specification of Letters Patent. Patented Mar. 18, 1913.

Application filed May 18, 1906, Serial No. 317,463. Renewed July 25, 1910. Serial No. 573,639.

To all whom it may concern:

Be it known that I, JOHN D. MORGAN, a citizen of the United States, residing at Summit, in the county of Union and State 5 of New Jersey, have invented new and useful Improvements in Typographic Machines, of which the following is a specification.

The invention relates to typographic machines and, more particularly, to machines in which lines of type are automatically set up, justified, inked and impressions taken therefrom on surfaces suitable for reproduction so as to produce printing surfaces, 15 or upon surfaces which may themselves be used as printing surfaces.

Objects of the invention are to provide a machine of the character indicated which yields a product adapted for use in planographic or other printing or in securing a planographic or other printing surface; to provide a machine whereby impressions are made from a composed, justified and inked line of types upon a plurality of impression-receiving surfaces; to provide for taking an impression from each line of types upon each of a plurality of impression-receiving surfaces; to provide for composing the line of types from a key-board; to provide for automatic justification, alinement and inking of the line of types; to provide for the handling of the various impression-receiving surfaces; to provide for the handling of each surface 35 so that succeeding impressions may be properly arranged thereon; to provide for cleaning and distributing the types; and to provide for other functions necessary or desirable in connection with the operation of such a machine. These and other objects of invention will in part be obvious and will in part more fully appear herein.

The invention consists in the novel parts, improvements and combinations herein 45 shown and described.

The present invention contemplates, as hereinbefore indicated, composing, alining and justifying a line of types, inking the line of types, and then taking a plurality 50 of impressions therefrom upon suitable impression-receiving surfaces. In the em-

bodiment illustrated herewith by way of example a single impression from each line is taken upon each of the plurality of impression-receiving surfaces. When the impression-receiving surfaces are of sufficient extent and are otherwise adapted for taking a plurality of line impressions successively, the said surfaces may be moved between successive impressions so as to bring the lines 60 into columnar alinement upon the said surfaces. In this embodiment, therefore, it will be seen that as the successive lines of a composition are composed, justified, alined, inked, and otherwise operated upon 65 by the machine, an impression therefrom is secured upon each of the various impression-receiving surfaces carried by the machine and suitably arranged upon the said respective surfaces for reproduction. It will thus 70 be understood that several copies of the composed matter suitable for reproduction are provided from a single operation of the machine. Various kinds and forms of impression-receiving surfaces may be used in 75 the machine. The material may be in the form of sheets, such as sheets of transfer paper, sheets of offset material, or other suitable impression-receiving surface. A machine constructed in accordance with the 80 principles of the invention has, accordingly, been illustrated in the accompanying drawings and is described herein.

The invention contemplates, as indicated, the providing of mechanism for assembling 85 and justifying lines of types. Mechanisms of this character simply as such are old and well known in the art and it is immaterial, so far as regards many features of the invention, what particular kind of mechanism for effecting these functions is employed. It is also contemplated by certain features of the invention to distribute the line of types after impression has been made therefrom and the providing of suitable 90 mechanism for this purpose is also contemplated by the invention. As regards many features of the invention, it is likewise immaterial what particular form of such mechanism is used. In the embodiment of the invention herein illustrated and described by 95 way of example, the mechanisms for assem-

bling and justifying the lines of types and for afterward distributing the types are substantially similar to those of the well-known linotype machine, which are substantially set forth in United States Patent No. 436,532 to Ottmar Mengenthaler and patents and applications referred to in the said patent. Many parts of the mechanisms shown and described in the said patent not being useful in connection with the present invention are not shown or described in this application. It will be understood that the use of portions of the machine mentioned is not restrictive but merely illustrative in character.

The accompanying drawings, referred to herein and forming a part hereof, illustrate one embodiment of the invention, the same serving in connection with the description herein to explain the principles of the invention.

Of the drawings: Figure 1 is an end elevation of a machine constructed in accordance with the principles of invention; Fig. 2 is a front elevation of such a machine; Figs. 3 and 4 are partial plan views with parts broken away; Figs. 5 and 6 are detail elevations, partly in section, of parts of the mechanism Figs. 7, 8, 9, 9^a, 10 and 11 are detail views of one form of carriage mechanism and associated parts; Figs. 12, 13 and 14 are detail views of another form of carriage mechanism and associated parts; Figs. 15, 16 and 17 are detail views of parts of the driving mechanism; Figs. 18, 19 and 20 are details, partly in section, of the justifying mechanism; and Figs. 21 and 22 show the action of the alining devices when in engagement with the line of types and when passing out of engagement therewith.

Referring to the illustrated embodiment of the invention, and for the present to the forms of composing and justifying mechanism shown in connection therewith, A indicates a magazine for holding types, said magazine being divided into compartments corresponding to the different characters used in the machine. Suitable mechanism for selecting types from the compartments of the magazine in the order required for the matter being composed is provided, said mechanism being controlled by the keyboard B so that upon the actuation of a key the type bearing the corresponding character is released from the magazine and transferred to its proper place in the line which is in process of assembling.

C indicates the assembling block wherein the successive characters forming the line as released from the magazine by operation of the keyboard B are assembled, together with suitable interverbal spacing devices 2^a, generally known as space bands, for separating words. The said interverbal spacing devices may be varied in their dimen-

sions so as to effect the justification of the line by varying the extent of the word spaces. In the illustrated machine these space bands 2^a are expandable so as to separate the words in the line to fill out the predetermined line measure. The magazine D is shown for the space bands from which they are fed down by suitable mechanism at the proper points in the assembling line in the block C. After a complete line has been assembled it is elevated to the guide E, from thence to the vertically movable yoke F, and from thence the line is carried to the clamping devices G. Here the line is positioned and the line is justified by the justifying mechanism J. The justifying mechanism is shown only in part in the general views in the accompanying drawings, being omitted for the sake of clearness, and the form thereof being well known.

The specific construction of the parts above mentioned, as has been stated, are not included in the present invention and it is not, therefore, necessary to describe them more fully in this connection. The said mechanisms serve to position and justify the line as indicated.

The types used may be generally similar to the well-known matrix of the linotype machine, being provided with shoulders for co-operating with the magazine escapement mechanism, the alining devices, and having also distributing devices, but having a type face which is adapted for printing rather than casting.

Suitable devices are shown herein for alining the composed and justified line of types prior to the impression, such devices being shown as comprising a member 1 adapted to engage the forward heel of the line of types prior to the impression, and to move out of engagement therewith before the line is removed for distributing, the said member being actuated by suitable connections with one of the cam shafts. As herein shown a link 1^a leads from the aliner to bell crank lever 1^b which is in operative relation with cam 1^c on shaft 23. The line of types is then ready for inking and for giving an impression upon a suitable surface. In the illustrated embodiment of the invention, means are provided for handling two sheets or webs of impression-receiving material, although different numbers of sheets may be used. Also, so far as concerns certain aspects of the invention, other forms of impression-receiving material may be used. The invention further contemplates the application of a suitable medium to the face of the types for making an impression upon the impression-receiving surface, such as a suitable ink. In the illustrated embodiment, when a line of types has been composed, justified and inked by the machine, 130

the said line and each of the impression-receiving surfaces are brought into impression contact in succession, so that each surface receives an impression from each line of types. The said surfaces in the present embodiment are given a line-space movement so as to bring successive lines in column alinement upon the said surfaces. Other features are included in the invention and will be set forth herein.

In the illustrated embodiment of the invention, the impression-receiving surfaces are mounted upon suitable holding or supporting means, carried upon a carriage and this carriage is constructed and arranged to reciprocate toward and from the fixed line of types for the impression contact, and the various holders or supports for the impression-receiving surfaces are automatically movable upon the carriage to bring the impression-receiving surfaces successively into position to receive impression from the line of types, or other character-impressing means. Referring to the drawings herewith the line of types in the printing position is represented by the reference numeral 2. The said line will have been justified and alined by the mechanism hereinbefore indicated or by other suitable mechanism. As hereinbefore indicated, the present illustrated embodiment of the invention is designed to operate upon two impression-receiving surfaces, and the said surfaces are indicated in the drawings by reference numerals 3 and 4, respectively. Suitable holding or supporting means for the said surfaces are provided, and the form of such means shown in the drawings comprises a platen member 5 located back of each of the impression-receiving surfaces along the impression line. Said means in the illustrated form comprise also devices for assisting in supporting the impression-receiving surfaces, or sheets, and for giving a line-space feed thereto, which are shown in the drawings as sets of rollers 6 and 7 carried contiguous to the platen 5. It is desirable to have a positive and exact feed movement of the impression-receiving material, and suitable means for effecting this may be provided. Herein such means are shown as sprocket teeth carried upon the rolls which engage with sprocket holes in the margins of the impression-receiving material as indicated by reference numeral 3^a in Fig. 9^a of the drawings. All the said devices for supporting and feeding the impression-receiving surfaces are shown in this embodiment as mounted upon a suitable carriage, the general structure of the carriage being indicated by the reference numeral 8. In this embodiment, as hereinbefore indicated, the line of types is held in fixed position during the impression operations and the carriage is arranged to reciprocate to-

ward and from the line of types so as to bring the impression-receiving surfaces into impression contact therewith to receive impression therefrom. The carriage is therefore shown as being mounted upon guides 9 suitably supported by the frame of the machine. Suitable devices for moving the carriage to and from impression are provided which will be later described in detail. For the purpose of providing a yielding impression during impression contact so as to secure a uniform impression or imprint throughout the extent of the line suitable means are contemplated by the present invention. In the illustrated embodiment the form of such means comprises a yielding mounting for the platen 5 with reference to the carriage structure 8. For this purpose the part 5 is movable in guides on the carriage in a plane normal to the face of the line of types when at impression contact and is held to position by suitable yielding means shown herein as springs 10, having tension-adjusting means, such as the adjustable screws 11. This arrangement provides for the platen 5 giving or yielding whenever a certain predetermined pressure is exceeded at any portion of the line thus giving a uniform impression for successive lines and the parts of each line.

As hereinbefore indicated suitable means are contemplated by the invention for moving the impression-receiving surfaces successively into position on the carriage to receive impression from the line of types as the carriage moves forward for the impression, the carriage moving forward for such impression once for each impression-receiving surface carried by the carriage. With the illustrated machine the carriage would make two reciprocations for each line of types presented at the printing point so that each of the two impression-receiving surfaces would receive an impression therefrom. One form of means for moving the impression-receiving surfaces into impression position is shown in Figs. 7 to 11 of the drawings. With this form also the impression-receiving material is shown in the form of single sheets, although a web, or other suitable form of surface might be used. Each of the holders or supports, including in this embodiment the platen 5 and rolls 6 and 7, for the impression-receiving material is shown as being provided with guides or aprons 12 for guiding and protecting the sheet. In the form illustrated in the said figures the said supports for the impression-receiving sheets are shown constructed and arranged to rotate about a horizontal axis 125 or shaft 13 carried by the carriage structure 8, the said supports for the impression-receiving sheets being at opposite ends of arms 14 fixed to the said shaft 13. The two impression-receiving sheets shown in the

illustrated embodiment are successively brought to position by semirotations of the shaft 13, and suitable means for effecting this movement are provided, the form of such means shown herein comprising a pinion 15 fixed on the shaft 13. The said illustrated form also comprises a reciprocating rack bar 16, the said bar being shown as held to position at one end of its movement by a suitable spring 17 and as having bell crank levers 18 and 19 in operative connection therewith to move it positively in the opposite direction against its spring 17. The bell crank lever 18 is in operative connection with the cam 20 upon a shaft 21, and the bell crank lever 19 with the cam 22 upon the shaft 23. For the purpose of positively bringing the impression-receiving surfaces to rest at the impression point a disk 24 is shown carried fixedly upon the shaft 13. The said disk has cam notches therein adapted to coöperate with a spring-pressed cam finger 25 having an end shaped to enter the said notches as they come into register therewith so as to accurately position the impression-receiving material and the platen 5 in the impression position. The rotation of the shaft 13 to cause the successive presentation of the impression-receiving surfaces at the impression point occurs in the present embodiment, as will be seen, when the carriage is away from impression and while the pinion 13 is in engagement with the rack bar 16. The cam finger 25 is at this time thrown out of engagement with the cam notch in the disk 24 by suitable means. It is shown so shaped that its tail contacts with a suitable surface upon the rack bar 16, so that it is cammed out of engagement with disk 24, as clearly shown in Figs. 7 and 8 of the drawings.

Suitable line spacing means are provided for positioning successive line impressions in column alinement upon the impression-receiving surface. In the illustrated form thereof one of the pressure rolls 7 is shown provided with a ratchet wheel 26 rotating fixedly therewith. A pawl 27 is constructed and arranged to co-act with the said ratchet wheel, said pawl being mounted upon a rotatable arm 28, the arm 28 being actuated by contact with the lug 29 so as to give a line-space feed after each impression of a line of characters upon the impression-receiving surface.

In the form shown in Figs. 12, 13 and 14 of the drawings, the supports for the impression-receiving material are shown adapted to rotate in a horizontal plane in order to pass into the impression position.

The impression-receiving material is also shown as being carried in the form of a web, although it will be obvious that the impression-receiving material could be used in other forms if desired. The impression-receiving material is further shown herein

as being carried upon a roll 30 and as being fed out in sheets. If desired, however, it could be taken up on a roll 31. The two platens 5 are shown in the present form as mounted at the opposite ends of arms 32 fixed upon a vertical shaft 33 carried by the carriage 8. A pinion 34 is shown fixed with relation to the shaft 33 for the purpose of giving it the proper movement for bringing the impression-receiving surfaces to the impression point, the said pinion engaging with a rack bar 35 herein shown as being horizontally movable and as being spring-held in one direction by the spring 36. The said rack bar is also shown pivotally connected to a bell crank lever 37 which is in operative relation with the bell crank levers 18 and 19 for the purpose of moving the rack bar 35 against its spring to rotate the shaft 33. For feeding the impression-receiving material, a ratchet wheel 38 is shown fixed to the roll 31 and provided with a pawl 39, carried by an arm 40. The arm 40 is actuated by a suitable tripping lug 41 upon the carriage 8. To accurately center the supports for the impression-receiving material at the impression point a cam disk 42 is provided, having notches coöoperating with a cam finger 43. The finger 43 is thrown out from the notches at the proper time by coming in contact with a face upon the rack bar 35 so as to allow the supports for the impression-material to rotate into and out of the impression position.

Suitable devices are provided for applying a proper medium, such as an ink, to the face of the line of types. In the illustrated embodiment the form of such means comprises a reciprocating carriage 44, carrying inking rollers 45, and moving in ways 46 past the face of the line of types then in printing position, so that the inking rollers 45 will contact with the type faces to supply the necessary ink. Suitable means for reciprocating the inking carriage 44 are provided, the form thereof herein shown comprising a rack bar 47 which is engaged by a pinion 48 mounted upon a shaft 49. The shaft 49 is connected by gears 50 to shaft 51, whose pinion 52 is in mesh with a geared sector 53 carried upon a pivoted arm 54 which is controlled by cam 55 upon shaft 21.

An ink supply of any suitable form is provided for the inking rolls 45 and in the illustrated form comprises ductor rolls 56 and a distributing plate 57 and suitable actuating mechanism therefor. In the illustrated embodiment the inking carriage is constructed and arranged to give one reciprocation previous to each impression, and thus to give two inkings to each line, although it will be manifest that the inking could be varied as desired for various kinds of work.

The various parts of the machine may be actuated in any suitable manner, as may be found convenient, but in the present embodiment two cam shafts 21 and 23, hereinbefore referred to, are provided, the movement of the two shafts being properly regulated to correspond to the relation of the functions of the machine to each other and to the duties placed upon each shaft. As hereinbefore described, the movement of the supports for the impression-receiving surfaces is controlled from both shafts, one movement being given from one shaft and the next from the other. The movement of the carriage to and from impression is also controlled from both shafts. In the illustrated form of actuating connection for the carriage, a pivoted link 58 is shown connected to the carriage and to a bell crank lever 59, mounted upon the frame of the machine and being in operative relation to a cam 60 upon the shaft 23 and also a cam 61 upon the shaft 21. The carriage is thus carried to impression contact with each line 25 of types, once from one shaft and once from the other.

Controlling and driving means of a suitable and convenient form are provided for the cam shafts 21 and 23, and the specific form thereof comprised in the illustrated embodiment is shown more particularly in Figs. 3, 15, 16 and 17 of the drawings. The said controlling and driving means are designed to bring the cam shafts and their associated mechanisms into action and to rest at the proper times with respect to the completion of the composition of a line by the operator, and also with respect to the duties and functions placed upon each of the cam 40 shafts respectively.

A suitable power shaft is indicated by the reference numeral 62. A pinion 62^a on the said shaft meshes with a gear wheel 62^b on shaft 23. Loosely sleeved upon the shaft 62 45 is a constantly rotating pulley 63, driven from a suitable source of power. Between the said shaft 62 and pulley 63 there is a clutch connection 64. The said clutch, as shown, is fixed to the shaft 62 and is controlled by an arm 65 which swings on its shaft 66, permitting the spring 67 to carry clutch 64 into engagement with the pulley 63, thereby starting the shaft 62 into rotation. To the shaft 66 is fixed an arm 68 55 which has a pin-and-slot connection with the end of a slidable rod 76, hereinafter referred to. Pivoted also to the said shaft 66 is an arm 69 arranged to be normally in position to engage the stop latch 70 carried by the wheel 71 on the shaft 23. Contiguously mounted to the mechanism just described is a shaft 72 having an arm 73 thereon adjacent to the arm 69 and having another arm 74 in position to be engaged by a lug 65 75 upon the rod 76. The shaft 72 is held

in position by suitable means such as the spring 78. A connection is provided for automatically calling the said parts into movement when the line is elevated from the assembling point to the slide E on its way to the automatic alining and justifying devices. The said connections comprise a rock shaft 77^a having an arm operatively connected to the line-elevating mechanism and an arm adapted to release latch 70 through the action of arm 73 so as to free shafts 62 and 23 for rotation and allow the arm 65 to throw in the clutch 64. A handle 77 is attached to rod 76 so that the said parts may be manually controlled when desired. For this purpose there is a lug 75 on rod 76 adapted to act on arm 74 and through shaft 72 and arm 73 release latch 70. After a line has been assembled the operator by means of the handle B¹ moves the line from the assembling point up to the guide E and the shaft 77^a is also rotated so as to throw in the clutch 64 and release the latch 70 so that the shafts 62 and 23 are connected and free to rotate with the driving pulley 63, as just described.

With the illustrated arrangement of mechanism, the shaft 23 rotates for the performance of the duties of transferring the line to the printing position, justifying, alining and clamping it prior to impression. The shaft 23 is thereupon brought to rest and the shaft 21 called into rotation by suitable mechanism. To effect this, there is provided in addition to the spring latch 70, upon the wheel 71, a latch 79 which co-acting with the stop arm 69 brings the shaft 23 to rest, and throwing out the clutch 64 allows the shaft 62 also to come to rest.

Suitable means for rotating the shaft 21 are provided and in the present embodiment includes a gear wheel 80 bolted to the driving pulley 63, the said gear wheel 80 being in mesh with an intermediate 81 which meshes with another intermediate 82. Loosely mounted upon the shaft 83 in train between the said gear wheel 82 and the shaft 83 is a suitable clutch mechanism 84, serving to throw the gear wheel and shaft into and out of motion. Fast upon the shaft 83 is a gear 85 meshing with a gear 86 upon the shaft 21. Suitable devices are provided for releasing the shaft 21 and throwing in the clutch 84, said devices being constructed and arranged to time the action of the shaft 21 in harmony with that of the shaft 23 as previously indicated. For this purpose a shaft 87 is shown mounted adjacent to the shafts 66 and 72, said shaft having an arm 88 thereon, adapted to coact, in a manner which will be more fully explained hereinafter, with the spring latch 89 upon the wheel 90, carried by the shaft 21. Mounted conveniently adjacent to the said parts is an arm 91 having fixed 130

therewith an arm 92, the free end of the arm 92 being adapted to co-act with a cam lug 93 carried upon the wheel 71.

The shaft 21, in the illustrated embodiment, when called into rotation acts to bring the impression-receiving material into the impression position, to ink the line of types, to carry the carriage forward for the impression and to again ink the line of types preparatory to the second impression. At this point the shaft 21 is brought to rest and the shaft 23 again called into rotation. For this purpose there is provided in the present embodiment a trip arm 94 carried upon the shaft 72, the operation of which will be hereinafter fully described. The shaft 23, when again called into rotation, as just above indicated, rotates to move the other support for the impression-receiving material into the impression position, to carry the carriage forward for the second impression and then to actuate the proper mechanisms to perform the remaining duties, including the distribution of the line.

The manner of operation of the mechanism herein described is substantially as follows: The mechanism of the keyboard B is operated in a well-known manner so as to permit the types corresponding to the various keys which are actuated to escape from the magazine A and to be assembled in the order of the actuation of the keys in the assembling block C. The space bands are also fed down from their magazine D into the assembling block in their proper places with reference to the types so as to separate the words in the line. The completed line is transmitted through the guide E to the yoke F and is positioned in proper relation to the clamping devices G and justifying devices J. To accomplish the movement of the line of types, as briefly outlined above, and also to perform the succeeding functions, the shaft 62 and the cam shaft 23 are brought into action. This is effected by the operator lifting the composed line to the guide E, the shaft 77^a being rotated so that its arm causes arm 73 to move latch 70 against its spring and thus release arm 69 and, through shaft 66, allows lever 65 to move back, permitting the clutch 64 to connect shaft 62 and pulley 63. The pulley 63 then serves to drive the shaft 62 and, through the gears 62^a and 62^b, the shaft 23. The line of types is then justified, alined and clamped in position by the action of the proper mechanisms, comprising certain cams carried by the shaft 23, during a partial rotation of the said shaft. About this time the lug 93 upon the wheel 71 contacts with the end of the crank arm 92 and the latch 79 comes in contact with the arm 69. Latch 79 cams arm 69 back into its original position, as shown in Fig. 16, by which action

the arm 65 is made to move against the spring 67 to throw out the clutch 64 and the shafts 23 and 62 are thereby brought to rest. The movement of the arm 92, however, as above set forth, serves through the arm 91 to throw out the spring latch 89, releasing the shaft 21. Also through the action of the shaft 87 and the arm 87^a, when arm 88 is released from latch 89, the clutch 84 moves in obedience to the action of its spring so as to bring the shaft 83 and the loose gear 82 into engagement, and thereby, through the gear 85, causing the rotation of the shaft 21. The rotation of the shaft 21 serves, through the cam 55 to move the sector 53 which, through the pinion 52, shaft 51, gears 50 and shaft 49, to rotate the pinion 48. The rack 47 is thus actuated to cause the inking carriage 44 to pass across the line of types, which are inked by the rollers 45. The bell crank lever 18 is actuated by its cam 20, carried by the shaft 21, to move the rack bar 16 against its spring 17 to rotate the pinion 15 and therewith the arms 14 so as to bring the impression-receiving material to the impression position, the spring cam finger 25 serving with the cam notch in the disk 24 to center the impression-receiving material accurately prior to the impression. As the arms 14 with the supports for the impression-receiving material swing into position the pin 29 co-acts with the line spacing lever 28 of the other feeding and supporting mechanism to feed up the impression-receiving material to bring the lines into column alinement. The carriage is now moved to and from impression through the bell crank lever 59 being actuated by the cam 61 upon the shaft 21. The cam 55 again causes a re-inking of the line substantially in the manner first described above. The shaft 21 now comes to rest and the shaft 23 is again called into rotation. To effect this the spring latch 89 contacts with the arm 94 thus rocking the shaft 72 which serves to swing the stop arm 73, striking the latch 79 and causing the associated mechanism to bring the shafts 23 and 62 into rotation as in the manner hereinbefore described. The latch 89 in the meantime has cammed the arm 88 into position so as to throw off, through shaft 87 and arm 87^a, the clutch 84 against its spring. The arm 88 then serves to hold the shaft 21 in its proper position of rest. The bell crank lever 19 is now actuated by means of its cam 22, carried upon the shaft 23, and the arms 14 are again rotated to bring the other impression-receiving surface to the printing position, the other related mechanisms, such as the centering devices and the line spacing devices, operating to again perform their functions substantially in the manner hereinbefore set

forth. The carriage then goes forward to impression and back, the bell crank lever 59 now being actuated to effect this by its cam 60, carried upon the shaft 23. The aliner 1 and the clamping mechanism for the line now pass out of engagement therewith, and the line is passed over to the distributing devices, indicated generally in the drawings by reference character L. The 10 said mechanism is constructed and operates in substantially the manner of the corresponding mechanism in the well-known linotype machine.

When desired a suitable cleaning device 15 for the types may be used and there is shown in the drawings herewith a cleaning device, indicated generally by the letter K, the same being substantially of the same general type as that described in detail in 20 application for Patent Ser. No. 203,713 filed April 18, 1904.

With the form of carriage and support for the impression-receiving material shown in Figs. 12 to 14 inclusive of the drawings, 25 the manner of operation is substantially the same as hereinabove set forth. It will be noted however that the swinging support for the impression-receiving material moves in a horizontal instead of a vertical path 30 and that the actuating rack bar 35 moves also in a horizontal instead of a vertical path. To provide for this motion the bell crank levers 18 and 19 instead of acting directly upon the rack bar act through the 35 medium of a bell crank 37, which serves to move the rack bar 35 against its spring 36, so as to give the semirotations to the arms 32 and the supports for the impression-receiving material. The cam finger 43 serves 40 to accurately position the impression-receiving material for the impression and the arm 40 serves to effect the line spacing by contacting during its movement with a lug 41.

From all the foregoing it will be understood 45 that a mechanism has been provided in accordance with the principles of the invention which realizes the objects of invention and the advantages set forth, together with other objects and advantages:

The invention, in its broader aspects, is not limited to the particular constructions shown, nor to any particular constructions by which it has been or may be carried into effect, as many changes may be made in the 55 construction without departing from the main principles of the invention and without sacrificing its chief advantages.

What I do claim as my invention and desire to secure by Letters Patent, is:

1. A typographic machine including in combination means for composing a line of types, means for justifying the line of types, means for inking the line of types, means for holding a plurality of impression-receiving

surfaces, and means for bringing the 65 impression-receiving surfaces and the line of types into impression contact.

2. A typographic machine including in combination means for composing a line of types, means for automatically justifying 70 the line of types, means for alining the line of types, means for inking the line of types, means for holding a plurality of impression-receiving surfaces, and means for taking a plurality of impressions from 75 said line of types upon the impression-receiving surfaces.

3. A typographic machine including in combination means for composing a line of types, means for automatically justifying 80 the line of types, means for inking the line of types, means for holding a plurality of impression-receiving surfaces, and means for bringing the impression-receiving surfaces and the line of types into impression 85 contact, so that each of the said surfaces will receive an impression from the line of types.

4. A typographic machine including in combination means for composing a line of types, means for justifying the line of types, 90 means for inking the line of types, a plurality of supporting means each carrying an impression-receiving surface, means for bringing a plurality of said surfaces and the line of composed and inked types into impression contact, and means for moving each 95 of the impression-receiving surfaces prior to impression by a succeeding line of types.

5. A typographic machine including in combination means for composing a line of 100 types, means for justifying the line of types, means for inking the line of types, a plurality of supporting means each carrying an impression-receiving surface, means for bringing a plurality of said surfaces and the 105 line of composed and inked types into impression contact, and means for moving each of the impression-receiving surfaces so as to receive impressions from successive lines of types upon the said surface in column alignment. 110

6. A typographic machine including in combination means for composing a line of types, means for justifying the line of types, means for inking the line of types, means for holding a plurality of impression-receiving surfaces, means for bringing the impression-receiving surfaces and the line of types into impression contact, and means for causing a yielding action during the impression. 120

7. A typographic machine including in combination means for composing a line of types, means for justifying the line of types, means for inking the line of types, a plurality of supporting means each carrying 125 an impression-receiving surface, means for bringing a plurality of said surfaces and the line of composed and inked types into

impression contact, and means for causing a yielding action on the part of the supporting means during impression.

8. A typographic machine including in combination means for composing a line of types, means for justifying the line of types, means for inking the line of types, means for supporting a plurality of impression-receiving surfaces and taking impressions upon each of the said surfaces from the said justified and inked line of types, and means for distributing the types.

9. A typographic machine including in combination means for composing a line of types, means for justifying the line of types, means for inking the line of types, a plurality of supports each carrying an impression-receiving surface, and means for bringing the said surfaces in succession into impression contact with the justified and inked line of types to receive impression therefrom.

10. A typographic machine including in combination means for composing a line of types, means for justifying the line of types, means for inking the line of types, a plurality of supports each carrying an impression-receiving surface, means for bringing the said surfaces in succession into impression contact with the justified and inked line of types to receive impression therefrom, and means for distributing the line of types.

11. A typographic machine including in combination means for composing a line of types, means for justifying the line of types, means for inking the line of types, a plurality of supports each carrying an impression-receiving surface, means for bringing the said surfaces in succession into impression contact with the justified and inked line of types to receive impression therefrom, and means for cleaning the types.

12. A typographic machine including in combination means for composing a line of types, means for justifying the line of types, means for inking the line of types, a plurality of supports each carrying an impression-receiving surface, means for bringing the said surfaces in succession into impression contact with the justified and inked line of types to receive impression therefrom, means for cleaning the types, and means for distributing the types.

13. A typographic machine including in combination a magazine for holding types, keyboard-controlled mechanism for selecting types from the said magazine for composing lines of types, means for justifying the composed line of types, means for inking the line of types, a plurality of supports each carrying an impression-receiving surface, and means for bringing the said surfaces into impression contact with the inked and justified line of types to receive impression therefrom.

14. A typographic machine including in combination a magazine for holding types, keyboard-controlled mechanism for selecting types from the said magazine for composing lines of types, means for automatically justifying the composed line of types, means for alining the line of types, means for inking the line of types, a plurality of supports each carrying an impression-receiving surface, and means for bringing each of the said surfaces into impression contact with the inked and justified line of types to receive impression therefrom.

15. A typographic machine including in combination means for composing a line of types, means for inserting interverbal spacing devices therein, means for varying the interverbal spacing devices so as to justify the line, means for inking the line of types, and means for supporting a plurality of impression-receiving surfaces and for bringing the said surfaces successively into impression contact with the line of inked and justified types to receive impression therefrom.

16. A typographic machine including in combination a magazine for holding various types, keyboard-controlled mechanism for selecting types from the magazine for composing lines of types, means for justifying the composed line of types, means for inking the line of types, means for holding a plurality of impression-receiving surfaces, and means for bringing the justified and inked line of types and the said impression-receiving surfaces into impression contact in order that the said surfaces may receive impression from the line of types.

17. A typographic machine including in combination a magazine for holding various types, keyboard-controlled mechanism for selecting types from the magazine for composing lines of types, means for justifying the composed line of types, means for inking the line of types, means for holding a plurality of impression-receiving surfaces, means for bringing the justified and inked line of types and the said impression-receiving surfaces into impression contact in order that the said surfaces may receive impression from the line of types, and means for moving each of the impression-receiving surfaces prior to impression by a succeeding line of types.

18. A typographic machine including in combination a magazine for holding various types, keyboard-controlled mechanism for selecting types from the magazine for composing lines of types, means for justifying the composed line of types, means for inking the line of types, means for holding a plurality of impression-receiving surfaces, means for bringing the justified and inked line of types and the said impression-receiving surfaces into impression contact in order that the said surfaces may receive im-

pression from the line of types, and means for moving each of the impression-receiving surfaces so that impressions from successive lines of types may be received thereon in column alinement.

19. A typographic machine including in combination a magazine for holding various types, keyboard-controlled mechanism for selecting types from the magazine for composing lines of types, means for justifying the composed line of types, means for inking the line of types, means for holding a plurality of impression-receiving surfaces, means for bringing the justified and inked line of types and the said impression-receiving surfaces into impression contact, and means for automatically distributing the types to the magazine.
- 10 20 25 30

20. A typographic machine including in combination a magazine for holding various types, keyboard-controlled mechanism for selecting types from the magazine for composing lines of types, means for justifying the composed line of types, means for inking the line of types, means for holding a plurality of impression-receiving surfaces, means for bringing the justified and inked line of types and the said impression-receiving surfaces into impression contact in order that the said surfaces may receive impression from the line of types, means for cleaning the types, and means for automatically distributing the types to the magazine.

21. A typographic machine including in combination a magazine for holding various types, keyboard-controlled mechanism for selecting types from the magazine for composing lines of types, means for justifying the composed line of types, means for automatically alining the line of types, means for inking the line of types, means for holding a plurality of impression-receiving surfaces, means for bringing the justified and inked line of types and the said impression-receiving surfaces into impression contact in order that the said surfaces may receive impression from the line of types, means for cleaning the types, means for automatically distributing the types to the magazine, and means for moving each of the impression-receiving surfaces so that impressions from successive lines will be received thereon in column alinement.

22. A typographic machine including in combination means for composing a line of types, means for justifying a line of types, means for inking a line of types, a carriage having a plurality of movable supports thereon each adapted to hold an impression-receiving surface, and means for moving the said supports with their impression-receiving surfaces successively into position to receive impression from the character-impressing means.

23. A typographic machine including in

combination means for composing a line of types, means for justifying a line of types, means for inking a line of types, a carriage having a plurality of movable supports thereon each adapted to hold an impression-receiving surface, means for moving the said supports with their impression-receiving surfaces successively into position to receive impression from the character-impressing means, and means for accurately positioning and holding the impression-receiving surface in position to receive the impression.

24. A typographic machine including in combination character-impressing means comprising character bearing members, automatic means for withdrawing impressed character bearing members and presenting new character bearing members, a carriage having a plurality of movable supports thereon each adapted to hold an impression-receiving surface, means for moving the said supports with their impression-receiving surfaces successively into position to receive impression from the character-impressing means, means for accurately positioning and holding the impression-receiving surface in position to receive the impression, and means for throwing out said positioning and holding means during the movement of the supports for the impression-receiving surfaces.

25. A typographic machine including in combination character-impressing means, a carriage having a plurality of movable supports thereon each adapted to hold an impression-receiving surface, means for moving the said supports with their impression-receiving surfaces successively into position to receive impression from the character-impressing means, and means for imparting a line-space movement to an impression-receiving surface during the moving of the surfaces successively to the impression-receiving position.

26. A typographic machine including in combination character-impressing means, a carriage having rotatable arms, each of said arms being provided with a platen and feeding devices for an impression-receiving surface, means for rotating said arms to bring the impression-receiving surfaces successively into the impression-receiving position, and means for actuating the feeding devices to impart a line-space movement to one of said impression-receiving surfaces during such movement.

27. A typographic machine including in combination character-impressing means, a carriage having rotatable arms, each of said arms being provided with a platen and feeding devices for an impression-receiving surface, means for rotating said arms to bring the impression-receiving surfaces successively into the impression-receiving position,

means for accurately positioning and holding the impression-receiving material in position to receive the impression, and means for actuating the feeding devices to impart 5 a line-space movement to one of said impression-receiving surfaces during such movement.

28. A typographic machine including in combination character-impressing means, a 10 carriage having rotatable arms, each of said arms being provided with a platen and feeding devices for an impression-receiving surface, means for rotating said arms to bring the impression-receiving surfaces successively into the impression-receiving position, means for accurately positioning and holding the impression-receiving material in position to receive the impression, means for throwing out said positioning and holding 15 means during the rotation of the said arms, and means for actuating the feeding devices to impart a line-space movement to one of said impression-receiving surfaces during such movement.

29. A typographic machine including in combination character-impressing means comprising character bearing members, automatic means for withdrawing impressed character bearing members and presenting 20 new character bearing members, guides for a carriage, a carriage reciprocable upon said guides to and from impression contact with said character-impressing means, said carriage having a plurality of movable means 25 for supporting impression-receiving surfaces, means for positioning and holding the impression-receiving surface during impression contact, means for throwing out said positioning and holding means, and means 30 for moving said plurality of supporting means so as to present successive impression-receiving surfaces at the impression point.

30. A typographic machine including in combination means for composing a line of 45 types, means for justifying the line of types, means for inking the line of types, a reciprocable carriage, said carriage having thereon a shaft having a plurality of pairs of arms, each pair of arms carrying a support 50 for an impression-receiving surface, a pinion on the said shaft, a movable rack bar located on the machine to engage said pinion when the carriage is away from impression, a disk having a cam notch fixed on said 55 shaft, a spring finger having a tooth in engagement with said cam notch, and means for throwing said finger out of said notch when the pinion and rack bar are in engagement.

31. A typographic machine including in combination means for impressing characters upon impression-receiving surfaces comprising character bearing members, automatic means for withdrawing impressed 60 character bearing members and presenting

new character bearing members, means for inking said character impressing means, a carriage carrying a plurality of impression-receiving surfaces, and means for successively positioning the said impression-receiving surfaces to receive inked impression from said impressing means. 70

32. A typographic machine including in combination means for composing a line of types, means for justifying the line of types, 75 means for inking the line of types, a carriage adapted to reciprocate upon guides toward and from the line of types, means upon the carriage for holding a plurality of impression-receiving surfaces, and means for bringing the said impression-receiving surfaces successively into position to receive impression from the line of types as the carriage moves between successive impressions of types. 80

33. A typographic machine including in combination means for impressing characters comprising character bearing members, automatic means for withdrawing impressed character bearing members and presenting 90 new character bearing members, means for inking said character impressing means, a carriage provided with means for supporting a plurality of impression-receiving surfaces, said supporting means being movable 95 to bring the successive surfaces into position to receive inked impression from the character-impressing means, means for bringing the character impressing means and the impression receiving material into contact, and means for positively registering the various impression receiving surfaces in position. 100

34. A typographic machine including in combination means for composing a line of types, means for justifying the line of types, 105 means for inking the line of types, a carriage provided with means for supporting a plurality of impression-receiving surfaces, said supporting means being movable to bring the successive surfaces into position 110 to receive impression from the character-impressing means, means for bringing the character-impressing means and the impression-receiving material into contact, and means for positively registering the impression-receiving surface in position. 115

35. A typographic machine including in combination means for impressing characters upon an impression-receiving surface, means for holding a plurality of impression-receiving sheets to receive a plurality of impressions from said character impressing means, means for moving said sheets successively into position to be impressed by the character-impressing means, means for bringing the positioned sheet and the character-impressing means into impression contact, and means for moving a sheet relatively to its holding means between successive impressions thereupon. 120 125 130

36. A typographic machine including in combination means for composing a line of types, means for justifying the line of types, means for inking the line of types, a carriage having means for supporting a plurality of impression-receiving sheets, means for moving said sheets into position to receive impression from the line of inked and justified types, means for bringing the positioned sheets and the line of types into impression contact, and means for moving a sheet between successive impressions so that the lines will be received thereupon in columnar alinement.
37. A typographic machine including in combination means for composing a line of types, means for justifying the line of types, means for inking the line of types, a reciprocating carriage having a movable member thereon provided with a plurality of holders for impression-receiving sheets, means for moving the carriage to and from the line of types to take impressions therefrom upon the sheets, means for moving said movable member so as to bring the sheets successively into position to receive impression from the line of types, and means for automatically moving the said sheets for columnar alinement between successive impressions thereon.
38. A typographic machine including in combination means for impressing characters upon an impression receiving surface, means for holding a plurality of impression receiving sheets, means for moving said sheets successively into position to be impressed by said character impressing means, means for bringing the positioned sheet and the character impressing means into impression contact, and means for moving a sheet a line space distance between the impressions whereby the impressions are made in page or column form.
39. A typographic machine including in combination means for impressing characters upon an impression receiving surface, means for inking said character impressing means, means for holding a plurality of impression receiving sheets, means for moving said sheets successively into position to be impressed by said character impressing means, means for bringing the positioned sheet and the character impressing means into impression contact, and means for moving a sheet a line space distance between the impressions whereby the impressions are made in page or column form.
40. A typographic machine including in combination means for impressing characters a line at a time upon an impression receiving surface, means for holding a plurality of impression receiving sheets, means for moving said sheets successively into position to be impressed by the character impressing means, means for bringing the positioned sheet and the character impressing means into impression contact, and means for moving said sheets successively into impression contact, and means for holding a plurality of impression receiving sheets, means for moving said sheets successively into impression contact, and means for bringing the positioned sheet and the character impressing means into impression contact, and means for causing a line space feed of the impression receiving surfaces between successive impressions thereon.
41. A typographic machine including in combination means for impressing characters a line at a time upon an impression receiving surface, means for inking said character impressing means, means for holding a plurality of impression receiving sheets, means for moving said sheets successively into position to be impressed by the character impressing means, means for bringing the positioned sheet and the character impressing means into impression contact, and means for moving a sheet a line space distance between the impressions whereby the impressions are made in page or column form.
42. A typographic machine including in combination means for impressing characters upon impression receiving surfaces, means for holding a plurality of impression receiving surfaces, means for moving said surfaces into position to be impressed by the character impressing means, means for bringing the positioned surface and the character impressing means into impression contact, and means for causing a line space feed of the impression receiving surfaces between successive impressions thereon.
43. A typographic machine including in combination means for impressing characters upon an impression receiving surface a line at a time, means for holding a plurality of impression receiving surfaces, means for moving said surfaces into position to be impressed by the character impressing means, means for bringing the positioned surface and the character impressing means into impression contact, and means for causing a line space feed of the impression receiving surfaces between successive impressions thereon.
44. A typographic machine including in combination means for impressing characters upon an impression receiving surface, means for inking said character impressing means, means for holding a plurality of impression receiving surfaces, means for moving said surfaces into position to be impressed by the character impressing means, means for bringing the positioned surface and the character impressing means into impression contact, and means for causing a line space feed of the impression receiving surfaces between successive impressions thereon.
45. A typographic machine including in combination means for impressing characters upon an impression receiving surface a line at a time, means for inking said character impressing means, means for holding a plurality of impression receiving sheets, means for moving said sheets successively into position to be impressed by the character impressing means, means for bringing the positioned sheet and the character impressing means into impression contact, and means for causing a line space feed of the impression receiving surfaces between successive impressions thereon.

into position to be impressed by the character impressing means, means for bringing the positioned sheet and the character impressing means into impression contact, and
5 means for causing a line space feed of the impression receiving sheets between successive impressions thereon.

In testimony whereof I have signed by name to this specification in the presence of two subscribing witnesses.

JOHN D. MORGAN.
